UNITED STATES PATENT OFFICE.

COLEMAN SELLERS, OF PHILADELPHIA, PENNSYLVANIA, ASSIGNOR TO
WILLIAM SELLERS & CO.

IMPROVEMENT IN WHEEL-PRESS.

Specification forming part of Letters Patent No. 35,127, dated April 29, 1862.

To all whom it may concern:

Be it known that I, COLEMAN SELLERS, of Philadelphia in the State of Pennsylvania, have invented a new and Improved Wheel-Press; and I do hereby declare the following to be a full and exact description thereof.

The object of my invention is to simplify the construction of permanent forcing-machines, used principally in the construction of railway machinery, and technically called "wheel-presses," so as to enable the same upright to be used either for pushing on or pulling off wheels from their axles.

The nature of my invention consists in the use of a permanent upright, on which is arranged the forcing machinery in connection with an adjustable upright capable of being readily moved into position for the work required to be done.

The manner of accomplishing this can be understood by reference to the accompanying drawing, making part of this specification, and which represents a side elevation of one of my improved presses.

The permanent upright A, securely fastened to a foundation of masonry, is provided in its center with a ram or plunger B, working in a cylinder, thus forming a powerful hydrostatic press. The power is conveyed to this press through the pipe C, which is connected with any ordinary pumping machinery, or the plunger B may be operated by a screw, if considered preferable. A second permanent upright, E, also bolted to foundation, is placed at a convenient distance from the upright A, and is designed only to hold in position the ends of the two tension bars F and G, the upper bar, F, consisting of a rectangular bar of iron, placed edgewise, strong enough to resist the tensile strain of the work to be done and stiff enough to carry the weight of an adjustable head or upright, H. This upright H is supported on the top tension-bar, F, by rollers I I, and can thus be readily moved to any required distance from the upright A. It is secured in its position by keys K K, passing through slotted holes in both bars F and G. The upright H is also notched out in its center at L to receive the axle when the machine is being used to push the axle out of the wheel, and is also convenient for receiving the protruding end of the axle when being forced into the wheel. The ram B has attached to it

a hinged piece, M, from which is suspended a loose blocking-piece, N. This blocking-piece has a recess in it to fit over the end of an axle, and it can be swung into position or removed to one side when it is desirable to bring the plain face of the ram against the work.

From the above description it is evident that the essential principle of my invention consists in using the same upright H both for putting on and taking off wheels, and in using the post E merely to hold the tension-bars in place and to support the weight of the adjustable upright H. In this respect it differs from all other wheel-presses, which, in general, are arranged with an upright in place of the post E strong enough to be used in pushing on wheels, while another upright, to be used in pulling off wheels, is either placed permanently in position near to the upright A or can be swung into position by a crane when needed, thus, in the first case, being very much in the way for many kinds of work, and, in the second case, difficult to adjust when required. In no instance, however, has one and the same upright been used for both purposes in an upright wheel-press. Hence the advantages to be gained by my invention are great ease of adjustment to work of different lengths and cheapness of construction.

I do not, however, limit my claim to the particular form of machine described, for it is evident to every ingenious mechanic that it may be modified in various ways, still retaining the same theory of operation—as, for instance, the rollers I may be placed at the bottom of the upright H, to run on the lower tension-rod G, or on a bed-plate which could be arranged in place of the lower tension-rod; but

What I claim as new, and desire to secure by Letters Patent, is—

1. The use of an adjustable upright, H, or its equivalent, substantially in the manner and for the purpose specified.

2. The hinged attachment of the blocking-piece N, or its equivalent, to the forcing-up plunger, substantially in the manner and for the purpose specified.

COLEMAN SELLERS.
